Arthur E. Randall, atty.

UNITED STATES PATENT OFFICE.

CHARLES D. JENKINS, OF BOSTON, MASSACHUSETTS.

MACHINE FOR MAKING BRIQUETS.

1,376,096.

Specification of Letters Patent. Patented Apr. 26, 1921.

Application filed May 1, 1915. Serial No. 25,135.

To all whom it may concern:

Be it known that I, CHARLES D. JENKINS, a citizen of the United States, and resident of Boston, in the county of Suffolk and State of Massachusetts, have invented certain new and useful Improvements in Machines for Making Briquets, of which the following is a specification.

My invention relates to molding machines, and particularly to machines of the class operating by rolling compression. The invention consists in a machine more particularly designed for making briquets from peat and the like, although not necessarily restricted to that particular use. The object of my invention is to provide an improved machine of the class in question.

The accompanying drawings illustrate an embodiment of the invention.

20. In the drawings,—

Figure 1 is a central vertical sectional view of the said embodiment.

Fig. 2 is a sectional detail hereinafter described.

25. Fig. 3 is a horizontal section on line 3—3 of Fig. 1.

The machine shown in the drawings comprises revolving pressing members consisting of a ring or annulus 3 and a wheel 2, the said wheel being eccentrically arranged within said ring or annulus. The periphery of the said wheel, as shown herein, works at one side against or close to the inner periphery of the ring or annulus 3. The two walls 4 and 5 of the chamber that is enclosed by the ring or annulus 3 are separate stationarily supported parts between which the ring or annulus 3 and wheel 2 are free to rotate. The wall 5 of said chamber rests upon posts 6, the two walls 4 and 5 being fastened to the said posts by bolts 7 extending through spacing-sleeves 8 which hold the two walls separated so as to leave the ring or annulus and wheel free to rotate between the walls.

The ring or annulus 3 is surrounded in part by a series of rolls 9 and 16 which serve to hold it in position to coöperate with wheel 2. The rolls 9 are given capacity for a certain outward yielding action. They are shown herein as having the journals of their spindles 10 fitted to boxes 11 that are

mounted in slots 12 provided in the walls 4 and 5, said slots being radial relative to the wheel. The boxes 11 of each pair are backed by springs 13 which are compressed between the boxes and a bar 14 that is mounted at its ends slidably in the slots 12. Each end of a bar 14 is supported with provision for adjustment by a screw 15 to vary the tension of the springs 13. This construction provides a yielding support for the rolls 9 so that the latter can yield under excessive pressure from ring or annulus 3, which will be desirable when operating upon some kinds of materials but not always necessary. That is, with some materials, the rolls 9 need not be yieldingly backed up. The side rolls 16 are mounted on spindles 17 journaled at their ends in bearings on walls 4 and 5.

The wall 3 is considerably larger in diameter than the wheel 2, which provides a crescent-shaped space 18 between said parts within one portion of which is arranged a hollow segmental shoe 19, the latter having a steam supply pipe 20, Fig. 1, communicating therewith, and also having a steam outlet 21 with which a steam exhaust pipe 22 connects. The inner side of shoe 19 is curved and is concentric with the axis of wheel 2 and arranged close to the periphery of the latter.

Adjacent one end of shoe 19 the wall 5 is made with an opening 23 which serves as an outlet for the molded articles.

The crescent-shaped chamber or space 18 within ring or annulus 3 is separated into two parts by a substantially radial partition wall 24 occupying a position alongside of outlet 23, said partition being conveniently an integral depending part of wall 4 and immediately adjacent an opening 25, Fig. 2, formed in said wall. This opening 25 is the entrance or inlet for the material that is to be treated, said material being deposited in a hopper 26 secured to wall 4 with its outlet registering with inlet 25. The material is forced out of hopper 26 into chamber 18 by a screw 27 carried by a shaft 28, one end of which extends through a bearing in connection with wall 5 and has fastened thereto a sprocket 29 (dotted lines Fig. 3) connected by a chain (not shown)

with a sprocket 31 fastened to the adjacent end of a shaft 32 journaled in bearings provided in walls 4 and 5, and to this shaft 32 is also fixed the wheel 2. Shaft 31 carries a 5 bevel gear 33 that is driven by a bevel gear 34 fast on a power driven shaft 35.

The wheel 2 is made with a plurality of radial pockets 36 in each of which is slidably mounted a plunger 37 carrying two 10 cam rolls 38 occupying corresponding cam grooves 39 formed upon the inner sides of walls 4 and 5.

During the operation of the machine the rotation of wheel 2 in the direction of the 15 arrow, Fig. 3, slides the rolls 38 along cam grooves 39. As each plunger approaches partition 24 it is moved outward by the cams to the limit of its outward radial movement, and as the plunger after passing 20 the partition 24 continues to travel around it is fully retracted by the cam grooves 39. During this inward movement of the plunger the outer end of its pocket is filled with the material occupying chamber 18 and 25 thereafter while the wheel moves a little less than ninety degrees and the plunger is traveling toward the point of coincidence between ring or annulus 3 and the inner periphery of ring 3, the plunger is moved 30 outwardly a short distance to assist in compressing the material within the pocket. In addition, as ring or annulus 3 and wheel 2 rotate, the material within chamber 18 is 35 compressed between their converging surfaces in the contracting portion of the said chamber so that thereby the material is forced to enter into the molding pockets, the excess material being held back.

After leaving the point of coincidence between the periphery of wheel 2 and the inner periphery of ring or annulus 3, each 40 plunger remains stationary within its pocket while the compressed material within the latter travels along the heating shoe 45 19, the heat from which serves to drive off moisture from said material. As each pocket nears the large end of shoe 19 the plunger 37 thereof is slightly retracted to break the adherence between the contents 50 of the pocket and the plunger and then, while the pocket is opposite outlet 23 the plunger is quickly shifted to the limit of its outward movement, thereby throwing the compressed material clear of wheel 2 55 and causing it to fall by gravity through outlet 23.

During the rotation of wheel 2 and ring or annulus 3 the feed screw 27 continuously supplies fresh material to chamber 18. 60 The drawings show the preferred arrangement of the parts of the machine, namely with the ring or annulus and wheel disposed so that their axes are vertical, so 65 that walls 4 and 5 constitute the top and bottom, respectively, of the chamber that

is inclosed by the ring or annulus. This arrangement, while not invariably adopted in the case of all embodiments of the various features of the invention, has several advantages. By having the feed-entrance 70 in the top wall 4, so that the material feeds downward into chamber 18, the tapering space within which the compression takes place is more readily kept properly filled, thereby insuring that the pockets of the 75 wheel shall be completely filled and shall contain uniform quantities of material. By having the ring or annulus and wheel arranged to work horizontally, it is made possible to construct the machine of a low 80 height, thereby enabling its receiving hopper 26 to be located below the discharge outlet of a preliminary machine from which it is desired that the material shall pass to the molding machine.

The wheel 2 is shown as having its periphery divided up into pockets each of which is in the form of a concavity extending transversely across the working face of the wheel. These concavities are 90 immediately contiguous, being separated from one another by comparatively thin partitions 24, so that they comprise practically the entire periphery of the wheel. In the rotation of the ring or annulus and 95 wheel the projecting portions of the partitions enter the mass of material which occupies the space between the converging walls of the ring or annulus and wheel, so that they operate to separate the said mass 100 into portions which are received within the pockets. Preferably, in order to facilitate their penetration into and through the mass of material, the outer portions of the partitions are made practically knife-edge.

What I claim is:—

1. A machine operating by rolling compression, comprising pressing members consisting of a ring and a wheel eccentrically arranged within the ring, and means yieldingly holding the wheel and ring in working relation to each other.

2. A machine of the character described comprising a pair of rotatable members consisting of a ring, a wheel eccentrically arranged within the ring, one of said members provided upon its periphery with molding pockets, and a heated shoe within the crescent-shaped chamber between said members, along which the molded material 11 is carried by rotation of said members.

3. A machine operating by rolling compression comprising an outer revolving ring or annulus, and an inclosed wheel eccentrically related to said ring or annulus, one 12 of said members having its periphery divided up into concavities extending transversely wholly across its periphery.

4. A machine operating by rolling compression comprising an outer revolving ring 13

or annulus, and an inclosed wheel eccentrically related to said ring or annulus, one of said members having its periphery divided up into concavities extending wholly across its periphery, with said concavities immediately contiguous one another and separated by partitions adapted to enter

into the mass of material occupying the tapering space between converging surfaces of the ring or annulus and wheel. 10

In testimony whereof I have affixed my signature.

CHARLES D. JENKINS.
